US00D633987S

(12) **United States Design Patent**
Thomas et al.

(10) **Patent No.:** US D633,987 S
(45) **Date of Patent:** ** Mar. 8, 2011

(54) **INTERFACE FOR A SINGLE HANDLE VALVE CARTRIDGE**

(75) Inventors: **Kurt Judson Thomas**, Indianapolis, IN (US); **Michael Scot Rosko**, Greenwood, IN (US); **Jeffrey L. Moore**, Frankfort, IN (US); **Derek Allen Brown**, Lizton, IN (US)

(73) Assignee: **Masco Corporation of Indiana**, Indianapolis, IN (US)

(**) Term: **14 Years**

(21) Appl. No.: **29/365,309**

(22) Filed: **Jul. 7, 2010**

Related U.S. Application Data

(63) Continuation of application No. 29/292,212, filed on Oct. 3, 2007.

(57) **CLAIM**

The ornamental design for the interface for a single handle valve cartridge, as shown and described.

DESCRIPTION

FIG. 1 is an upper perspective view of the interface for a single handle valve cartridge;

FIG. 2 is a lower perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the single handle valve cartridge that form no part of the claimed design.

1 Claim, 4 Drawing Sheets
